MODULATING SYSTEM

Hugh C. Ressler, West Brighton, N. Y., assignor to
 Faximile, Inc., New York, N. Y., a corporation
 of Delaware

Application September 14, 1940, Serial No. 356,751

5 Claims. (Cl. 179—171.5)

The present invention concerns electrical signal modulating systems and in particular balanced sub-carrier modulators.

One object of the present invention is to provide an improved method of, and means for modulating an alternating current signal.

Another object is to provide improved modulation of a sub-carrier tone in accordance with the output of a photo-electric cell.

A further object is to provide an improved balanced modulation system for alternating current signals.

A still further object is to improve the stability of balance in a balanced modulating system.

Another object is to provide a stable modulator which may be balanced at any predetermined point, as, for instance, at maximum, minimum or intermediate values of light falling on a photo-electric cell providing the source of modulation.

These and other objects will be apparent from the detailed description of the figure of the drawings.

One of the most satisfactory ways of transforming density variations of a picture or other facsimile subject matter into usable electrical signals is to scan the subject with a spot of light picking up the reflected light in a photo-electric cell and to utilize the photo-electric cell to modulate an alternating current having a frequency in the range of from 2,000 to 20,000 cycles. This alternating current is called a sub-carrier and after modulation it may be transmitted to a receiving and reproducing point over a wire line or after a further modulation of a radio frequency carrier it may be transmitted thru the air.

The modulation of the sub-carrier by means of the photo-electric cell has, hitherto, been considered to a certain extent unsatisfactory. The usual photo-electric cell is electrically equivalent to a very high resistance shunted by a small capacity. The variations in light from the subject falling on the photo-electric cell cause variation in this resistance. At the sub-carrier frequencies, however, the impedance of the cell capacity may heavily shunt the resistance and mask the desired changes in resistance. In order to overcome this difficulty, circuits have been devised for balancing the photo-electric cell capacity and a certain portion of its resistance. While this mode of operation is possible, it is critical and tends to be unstable, requiring a good deal of attention.

The present invention concerns a balanced

modulator in which the adjustments may be easily made and which is quite stable in operation. The output of the photo-electric cell is applied to the grid of a tube, causing variations in its plate resistance. The steady component of plate resistance is balanced by the controlled plate resistance of a second and similar tube. The sub-carrier to be modulated is fed into a balanced rectifier circuit and the modulation accomplished by unbalance between the two above mentioned tubes. Balance may be produced for white or black subject matter or at any intermediate point. The balancing adjustment is easily made and the system operates in a stable manner, requiring little attention.

In the drawings is shown a particular embodiment of the present invention, with curves to explain its mode of operation.

Figure 1 shows a "source of sub-carrier tone" 20 connected to primary 2 of the modulator input transformer 2—3—4. Secondary 4 is connected to primary 10 of the modulator output transformer 10—12—13 thru rectifiers 6 and 9. A third rectifier 7 is connected across the circuit between secondary 4 and primary 10 and a fourth rectifier 8 is connected across in the opposite direction. The combination of rectifiers 6, 9, 7 and 8 may be regarded as the four arms of a symmetrical lattice composed of resistors whose values may be changed by the voltage impressed across each resistor. Secondary 13 is connected to the "utilization means" 14 which may be a wire line, amplifier or other device for utilizing the modulated signals.

35 The modulation of sub-carrier signals is accomplished by means of tubes 17 and 18 connected to mid-tap 5 on secondary 4 and mid-tap 11 on primary 10 respectively. Tube 17 has at least a cathode 21, heated by conventional means not shown, control grid 20, and plate 19. Plate 19 is loaded by and receives current thru resistor 15 connected to battery 33. Plate 19 is also connected to mid-point 5 of secondary 4. Grid 20 is connected to cathode 26 of photo-electric cell 25. Cell 25 receives light from lamp 30—31 passing thru lenses 28 and 29 and modulated by subject matter on the surface of drum 32. Anode 27 of cell 25 is energized from tap 35 on battery 33 thru decoupling resistor 41. Anode 27 is by-passed by condenser 40. Tube 18 includes at least cathode 24, heated by conventional means not shown, control grid 23, and plate 22. Plate 22 is loaded by and receives plate current thru resistor 16 preferably substantially equal to resistor 15. Plate 22 is also connected

to tap 11 on primary 10. Control grid 23 is connected to variable tap 39 on potentiometer 38 which is bridged between points 36 and 37 on battery 33. Variation of point 39 along resistor 38 varies the balance thru the modulator. Cathodes 21 and 24 are connected to point 34 on battery 33.

In operation, the bridge formed by rectifiers 6, 7, 8 and 9 is balanced so that no sub-carrier voltage is transferred from coil 4 to coil 10 when the instantaneous potential of mid-point 5 is equal to the instantaneous potential of mid-point 11. Whenever point 11 has an instantaneous potential greater than point 5 current of one phase flows from coil 4 to coil 10 thru rectifiers 7 and 8 and whenever the instantaneous potential of point 11 is below the potential of point 5, sub-carrier current flows from coil 4 to coil 10 thru rectifier 6 and 9 in reversed phase. Thus, the magnitude and phase of sub-carrier signals passed thru the bridge rectifier are determined by the relative instantaneous potentials of points 5 and 11. The potential of point 11 may be adjusted by varying point 39 on potentiometer 38, controlling the bias on grid 23. The potential of point 5 varies in accordance with the light falling on photocell 25. The potential of point 11 may be made equal to point 5 for any particular light value on photocell 25 from zero to its maximum value. Thus, balance may be produced for maximum light and sub-carrier signal passed thru the bridge in proportion to the decrease in light from maximum due to the reflection coefficient of the subject on drum 32 or the balance may be made at zero light on photocell 23 and sub-carrier signals passed in proportion to the increase in light from zero. Many other balance conditions may be utilized, such as a balance at some predetermined light value, or a balance which passes a predetermined sub-carrier signal at zero light or at full light.

Rectifiers 6, 7, 8 and 9 should be so chosen that they will operate in a satisfactory manner in a given system. While not intended to limit the invention, it has been found that copper-oxide rectifiers having relatively small dimensions operate well to modulate a sub-carrier of 3000 cycles from a high speed facsimile pick-up. The circuit is useful, however, over a wide range of sub-carrier frequencies and with sources of modulating voltage other than the photo-electric cell shown.

This system has many advantages over prior devices. As described above, the balance point may be adjusted in any desired manner. The adjustment of balance is easily made or changed at will. By making tubes 17 and 18 similar, the stability of balance is very great, due to the fact that changes in supply voltages, ambient temperature, etc., affect the system symmetrically. It will be evident that the system may be operated with tube 17 connected to point 11 and tube 18 connected to point 5.

The current generated in photoelectric cell 25 in scanning a picture range in frequency from zero or direct current to an upper limit determined by the speed and resolution of the scanning system. Large areas of white in the scanned copy produce substantially steady photoelectric currents while large areas of black produce substantially no current for relatively long periods of time. It is important that the phase or sense of modulation be properly determined, so that the recorded copy will have a predetermined sense with respect to the original copy. If the recording mechanism is such that a mark

is produced by the audio sub-carrier and it is desired to mark on black, then the modulator system must be capable of suppressing the sub-carrier to nearly zero when the photoelectric currents attain their maximum value. In some cases it may be desirable to reverse the sense of transmission as, for instance, in the case of blue prints, where it is desired to produce a line drawing at the receiver from a blue print at the transmitter. The present system may be adjusted by means of potentiometer point 39 to produce full modulation for any value of light, on the photoelectric cell which permits positive or negative transmission and the predetermination of the "white" level.

Because of the very low frequency components of the photoelectric currents it is essential that the picture frequency components be suppressed either at the modulator or by means of filter circuits connected after the modulator. Such filter circuits are expensive and complicated, so that one of the great advantages of the present system lies in the fact that picture frequency components are suppressed in the modulator. At balance, the currents in the two halves of coil 10 are equal and in opposite directions and hence no net voltage is induced in secondary 13.

The present modulator operates as a so-called "side band" modulator. If the sub-carrier frequency is W_c and the picture frequency signal is W_p , then the modulator produces across coil 13 only the sum and difference frequencies $W_c + W_p$ and $W_c - W_p$. Both the picture frequency and sub-carrier frequency signals balance, producing no signals in the output coil 13. This eliminates the use of expensive and complicated filtering in the modulator output. Furthermore, the sense of modulation may easily be controlled, since the sub-carrier may be balanced for any predetermined value of light on the photoelectric cell. If the balance is made at maximum light, the modulation will be reversed in that "black" will produce maximum modulated signal output. On the other hand, if the balance is made on minimum light the modulation will be in the positive direction in that "white" will produce a maximum modulated signal output.

While one embodiment of the present invention has been shown and described, many modifications will be evident to those skilled in the art within the spirit and scope of the invention as set forth in the appended claims.

Fig. 2 shows a graph of the current in resistor 42 which would result from scanning a white bar and a gray bar against a black background. Going from left to right, the current is initially very small, due to the black background. Then it rises to a high value, due to the white bar. Next, it drops to a low value, again due to the black background. Then it rises to an intermediate value, due to the gray bar. Finally, it drops to a low value, due to the black background.

Fig. 3 shows the instantaneous potential of point 5. The greater the current flowing in resistor 42, the greater the positive voltage impressed on grid 20 and hence the greater the plate current drop in plate resistor 15. Thus, the potential of point 5 is high for black, drops to an intermediate value for gray, and drops to a low value for white. Lines a, b, c, d and e indicate some of the significant potentials to which point 11 may be adjusted by means of control 39. If the adjustment is made to place point 11 at a, the resulting modulation of the sub-carrier will be positive and less than 100 percent, as shown at f

in Fig. 4. With an adjustment made to *b* of Fig. 3, the modulation will be positive and 100 percent, as shown at *g* in Fig. 5. With an intermediate adjustment as shown by *c* of Fig. 3, no amplitude modulation will result, if the gray height is one-half the white, as shown at *h* in Fig. 6, although the sub-carrier phase will be reversed when point 5 changes sign with respect to point 11. With an adjustment at *d* of Fig. 3, negative modulation at 100 percent will result, as shown at *m* of Fig. 7. An adjustment to *e* of Fig. 3 will also give negative modulation, but of less than 100 percent, as shown at *n* of Fig. 8. By positive modulation is meant that the sub-carrier amplitude is greatest on white and by negative modulation is meant that the sub-carrier amplitude is greatest on black. Thus, it will be seen that a simple adjustment positive or negative modulation of any desired degree is obtainable.

What is claimed is:

1. A modulating system comprising four rectifiers connected together in a closed loop each with its better conductivity in the same direction around the loop, a center-tapped circuit coupled to a source of signals to be modulated connected across one pair of diagonal points of said loop, a second center-tapped circuit coupled to a load circuit connected across the other pair of diagonal points of said loop, a pair of thermionic vacuum tubes each including at least a cathode, a control grid and a plate, independent load circuits connected to each of said plates, conductive connections between one of said plates and one of said center-taps and the other of said plates and the other of said center-taps, a source of modulating signals connected to one of said grids for modulating the signals applied to said loop, and a source of bias connected to the other of said grids for balancing a predetermined instantaneous value of the second said signal across said loop.

2. In a modulating system the combination of, four rectifiers connected in a closed loop each with its better conductivity in the same direction, a transformer having a center-tapped secondary connected with its primary across a source of signals to be modulated and its secondary across one diagonal of said loop, a second transformer having a center-tapped primary connected with its primary across the other diagonal of said loop and its secondary across an utilization means, a pair of thermionic vacuum tubes each including at least a cathode, grid and plate, independent load circuits connected between said plates and a source of plate current, conductive connections between one of said plates and one of said center-taps and between the other of said plates and the other of said center-taps, means for applying signals to one of said grids for modulating the first said signals by means of said rectifiers, and means for applying an adjustable bias to the other of said grids for controlling the magnitude and phase of said modulation.

3. In a modulating system the combination of, four rectifiers connected in a closed loop each with its better conductivity in the same direction, a transformer having a center-tapped secondary connected with its primary across a source of sub-carrier signals and its secondary across one diagonal of said loop, a second transformer having a center-tapped primary connected with its primary across the other diagonal of said loop and its secondary across an utilization means, a pair of thermionic vacuum tubes each including at least a cathode, a grid and a plate, independent load circuits connected between said plates and a source of plate current, conductive connections between one of said plates and one of said center-taps and between the other of said plates and the other of said center-taps, a photo-electric cell connected to one of said grids for modulating said sub-carrier within said loop, and an adjustable bias source effectively connected to the other of said grids for balancing a predetermined component of said modulation within said loop.

4. A modulating system comprising four rectifiers connected together in a closed loop, each with its better conductivity in the same direction around the loop, a center-tapped circuit, coupled to a source of signals to be modulated, connected across one pair of diagonal points of said loop, a second center-tapped circuit, coupled to a load circuit, connected across the other pair of diagonal points of said loop, an electron stream operated vacuum tube including an output electrode normally maintained at a predetermined operating potential, means for modulating said electron stream, a conductive connection between said output electrode and one of said center-taps for applying the electron stream modulation to one side of said loop, and means for balancing a predetermined portion of said operating potential across said loop comprising a source of adjustable bias voltage connected to the second of said center-taps.

5. A modulating system comprising four non-linear resistors connected together in a closed loop, each with its better conductivity in the same direction around the loop, a center-tapped circuit, coupled to a source of signals to be modulated, connected across one pair of diagonal points of said loop, a second center-tapped circuit, coupled to a load circuit, connected across the other pair of diagonal points of said loop, an electron stream operated vacuum tube including an output electrode normally maintained at a predetermined operating potential, means for modulating said electron stream, a conductive connection between said output electrode and one of said center-taps for applying the electron stream modulation to one side of said loop, and means for balancing a predetermined portion of said operating potential across said loop comprising a source of adjustable bias voltage connected to the second of said center-taps.

HUGH C. RESSLER.
